(57) **CLAIM**

I claim the ornamental design for a teddy bear night lamp, as shown and described.

DESCRIPTION

FIG. 1 is a perspective view of a first embodiment of the teddy bear night lamp;

FIG. 2 is a front view of the teddy bear night lamp;

FIG. 3 is a rear view of the teddy bear night lamp;

FIG. 4 is a right side view of the teddy bear night lamp;

FIG. 5 is a left side view of the teddy bear night lamp;

FIG. 6 is a top view of the teddy bear night lamp;

FIG. 7 is a bottom view of the teddy bear night lamp; and,

FIG. 8 is a perspective view of a second embodiment of the teddy bear night lamp.

The broken lines in the drawings are for the purpose of showing portions of the teddy bear night lamp that form no part of the claimed design.

1 Claim, 5 Drawing Sheets
